DESIGN FOR A POWER CHAMBER

Edward Knauss, Berkeley, Calif., assignor to
Besler Systems, a corporation of California

Application June 13, 1939, Serial No. 85,945

Term of patent 14 years

To all whom it may concern:

Be it known that I, Edward Knauss, a citizen of the United States, residing at 1815 Hearst Street, Berkeley, in the county of Alameda and State of California, have invented a new, original, and ornamental Design for a Power Chamber, of which the following is a specification, reference being had to the accompanying drawing, forming a part thereof.

Figure 1 is a side elevation.

Figure 2 is a perspective view of the power chamber embodying the new design. The side of the power chamber not shown in the drawing is substantially the same as the side shown.

Figure 3 is a top plan view.

I claim:

The ornamental design for a power chamber, substantially as shown and described.

EDWARD KNAUSS.
